UNITED STATES PATENT OFFICE.

ELIHU THOMSON, OF SWAMPSCOTT, MASSACHUSETTS, ASSIGNOR TO GENERAL ELECTRIC COMPANY, A CORPORATION OF NEW YORK.

TORQUE-REGULATING MECHANISM.

No. 877,473.

Specification of Letters Patent.

Patented Jan. 21, 1908.

Application filed October 17, 1901. Serial No. 73,963.

To all whom it may concern:

Be it known that I, ELIHU THOMSON, a citizen of the United States, residing at Swampscott, county of Essex, State of Massachusetts, have invented certain new and useful Improvements in Torque-Regulating Mechanism, of which the following is a specification.

When an automobile is called upon to climb a grade, or to go over a heavy road, ¹⁰ *i. e.*, one which is sandy, muddy or rutty, it is necessary in order to maintain any reasonable speed to increase the torque of the motive power agency. This has been accomplished heretofore by means of suitable gearing, and also by increasing the torque of the engine by admitting more steam thereto. In both of these instances a mental and manual effort is required on the part of the operator. Where gearing is employed to effect the ²⁰ changes in torque, additional gears and levers must be employed which require attention to keep them in repair, and they also add complication to the vehicle. When the system is so arranged that more steam is admitted to the engine, there is danger of drawing too ²⁵ much steam and unduly reducing the temperature of the boiler.

The object of my invention is to provide a torque-regulating apparatus which is so arranged ³⁰ that it will act automatically to vary the torque of the engine or other motive device in accordance with the character of the route traveled over.

In carrying out my invention, the regulation is indirect, that is to say, it operates on the boiler. I may arrange the system so that the amount of fuel supplied to, or consumed by, the burner is varied, or I may regulate both the supply of fuel to the burner and ⁴⁰ water to the generator, as desired. Between the engine or motor and the driving wheel or wheels is located a device which is capable of assuming different positions as the power necessary to propel the vehicle varies. This ⁴⁵ device in turn controls the delivery of the fuel or fuel and water, so that as the load changes, the position of the regulating mechanism automatically changes and varies the admission of fuel and water.

With a given opening of the main throttle, ⁵⁰ the average steam pressure exerted on the piston or pistons for high speed running is less than that for low speed, therefore the torque of the engine for a given admission of steam ⁵⁵ will increase slightly as the speed drops, and

it is upon this change in torque that the operation of the apparatus depends. In other words, the change in torque and speed of the engine automatically changes the amount of ⁶⁰ fuel or the amounts of fuel and water supplied to meet the new conditions.

The scope of my invention will be more fully set forth and claimed hereinafter.

In the accompanying drawings, which ⁶⁵ illustrate an embodiment of my invention, Figure 1 is a partial plan view of a vehicle; Fig. 2 is an enlarged view in longitudinal section of a power-transmitting mechanism; Fig. 3 is a sectional view taken on the line ⁷⁰ 3—3 of Fig. 2; Fig. 4 is a plan of a power-transmitting mechanism; Fig. 5 is an end view thereof; Fig. 6 is an elevation of a slight modification wherein the effective strokes of the fuel and water pumps are varied; and ⁷⁵ Figs. 7, 8 and 9 are diagrammatic views illustrating a torque-regulating system wherein the actuating mechanism is controlled by the sprocket-chain.

Referring to Fig. 1, 1 represents an engine ⁸⁰ of any improved pattern; in the present instance a four-cylinder single-acting engine is illustrated. The steam for the engine is supplied by the generator 2 which is heated by the burner 3 illustrated in dotted lines. The ⁸⁵ rear axle is made in two parts 4 and 5, and motion is transmitted thereto from the engine by the sprocket-chain 6 and the differential gears 7. Between the differential gears and the rear driving sprocket 8 is arranged a ⁹⁰ spring, which will be more fully described hereinafter. Mounted on the ends of the driving shaft or axle are driving wheels 9, of any suitable character. Sleeved on the driving axle is a frame 10 that is prevented from ⁹⁵ rotating by a frame-bar 11, which extends to the forward axle or other support. The body of the vehicle 12 is indicated in dotted lines, as are also the water-tank 13 and the fuel-tank 14. Water is supplied to the generator ¹⁰⁰ or boiler from the tank 13 by the pipe 15, and fuel is supplied to the burner from the tank 14 by the pipe 16. The admission of water and fuel is regulated by the valves 17 and 18, which valves may be supported from the under side of the boiler-casing or at any other convenient point. These valves are so adjusted with respect to each other that they admit water and fuel in proportionate, or substantially proportionate, amounts. In ¹⁰⁵ the present instance the boiler 2 is of the flash

type, but other forms of boiler may be employed, such as shell or fire-tube. In the case of a flash or coil boiler, the apportionment of the deliveries of water and oil may be readily effected. The admission of steam from the boiler to the engine is controlled by the throttle-valve 19, and the exhaust leaves the engine by the pipe 20.

Referring more particularly to Figs. 2 to 5 inclusive, 4 and 5 represent the two parts of the driving-shaft or rear axle. The adjacent ends of the shafts are provided with bevel-gears 21 and 22. Surrounding these gears is a casing 23 which carries the pinions 24, the latter being arranged to mesh with the bevel-gears 21 and 22. The adjacent ends of the driving shaft or axle are somewhat reduced in section, and sleeved thereon is the rotatable support 25, in which the inner ends of the pinion-supporting shafts 26 are seated, the outer ends of these shafts being supported in the casing 23. The periphery of the casing is turned true, and may constitute the drum of a band-brake. The casing 23 is provided with a short sleeve or hub on the left-hand side, and with a long sleeve or hub 27 on the right-hand side, both of which hubs are loose on the axle. Mounted on the right-hand end of the hub 27 and retained against independent rotation by a spline 30 is a sleeve 31 that is capable of lateral motion. This sleeve is provided with a peripheral groove, in which is seated the split ring 32. The ring is provided with two radially extending pins 33, with which the slotted arms of the bell-crank lever 34 engage. The hub 27 of the gear-casing is also surrounded by the hub 28 of the rear sprocket-wheel 8. This hub is free to turn, independent of the casing 23 and its hub 27, within certain limits. The hub 28 of the sprocket-wheel is enlarged to form a box, and mounted in this box is a spiral spring 35. The outer end of the spring is rigidly secured to the sprocket 8, while the inner end is rigidly attached to the hub 27 of the casing 23. The arrangement of this spring is such that the sprocket-wheel 8 can be rotated forward or backward. It is essential that some form of spring connection or its equivalent be employed between the sprocket and the gear-casing 23, but the particular kind of spring employed may be varied to suit given conditions.

In cases where the vehicle is intended for service on roads which are more or less rough, it may be found desirable to provide some sort of a resistance device, such as a dash-pot, for example, to check the independent movements of the gear-casing or support 23 and the sprocket 8. The end face of the sprocket-wheel hub 28 is beveled or cut, as at 36, to form a cam, and engaging with this surface is a second cam-surface 37 formed on the left-hand end of the sleeve 31. Formed integral with the sleeve is a projection 38, which is ar-

ranged to engage with the projection 39 formed on the hub 28 of the sprocket-wheel, and limit the independent movement of these two elements.

While I have shown cam-surfaces on the meeting ends of the hub 28 and the sleeve 31, and depended upon them to measure or indicate the changes in torque, it is evident that other devices may be employed to accomplish the same purpose, and I aim to cover such devices in the claims.

The cam-surfaces 36 and 37 are normally held in engagement by the spring 40 (Fig. 1), one end of which is secured to the bell-crank lever 34, while the other end is secured to a bracket formed on the frame-piece 10. When the spring 35 in the sprocket hub is strained beyond a certain point, the sprocket-wheel tends to rotate independently of the sleeve 31, and this independent rotation forces the sleeve laterally along the spline 30. As the sleeve is displaced laterally, the position of the bell-crank lever 34 is changed, and one end of the lever engaging with the valve-stems moves in a manner to open the valves and permit more fuel, or fuel and water as the case may be, to enter the burner and boiler. When the mechanism is not in action the water and oil-valves would be practically closed, the oil-valve being open sufficiently to admit enough fuel to the burner to keep the parts hot. My improved apparatus may be used to regulate the entire admission of fuel to the burner and water to the boiler, or it may be used in conjunction with other regulating devices. Where a pilot-flame is employed to keep the parts hot, the fuel-valve 18 may be arranged to close entirely when the parts are at rest, as shown in Fig. 1.

In Fig. 6 is shown a slight modification of the system where, instead of controlling the admission of fuel and water through valves, the apparatus is arranged to vary the effective stroke of the fuel and water-pumps. 45 represents a water-pump, which is connected to the suction-pipe 46 and the delivery-pipe 47 in the ordinary manner. The end of the pump piston-rod is provided with a cross-head 48, that travels in suitable guides. To this cross-head is secured a connecting-rod 49, which rod is also attached to the adjustable block 50 in the link 51. Situated below the water-pump is a fuel-pump 52. The piston for this pump is rigidly connected to the piston of the water-pump, and moves in unison therewith. Power for driving the pumps is obtained from an eccentric 53, that is mounted on the driving axle 5, which eccentric has a definite stroke, and is pivotally connected to the slotted link 51. The bell-crank lever 34 is connected at one end to the laterally-moving sleeve 31, in the same manner as before. The other end is connected to the sliding block 50 by the pivoted arm 54. As the position of the sleeve 31 changes laterally,

due to the rotation of the sprocket-wheel 8 independent of it, the position of the block 50 is changed. When the block is in the lower end of the link, the strokes of the pistons are 5 at the maximum, and when it is at the upper end, they are at the minimum. The spring 40 tends at all times to reduce the stroke of the pump by moving the sliding block 50 upward. In this figure it is assumed that the 10 resistance to the rotation of the driving wheels is somewhat above normal, and that in consequence thereof the lug 39 on the sprocket-wheel has moved, as indicated by the arrow, through an angle of about 90 degrees 15 toward the lug 38 on the sleeve 31. In other words, the sleeve 31 has been moved laterally along the hub 27 of the gear-case and caused the bell-crank lever 34 to move the block 50 downward and increase the effective 20 strokes of the water and oil-pumps. The fuel and water-pumps are so adjusted with respect to each other that they will supply the proper portion of fuel to the burner and water to the boiler under changes of 25 load. In other words, sufficient fuel is supplied at all times to vaporize the water delivery to the generator. Steam taken from the generator 2 may be admitted to the engine, which in turn is connected to the driving axle that carries the eccentric 53; and since the eccentric is driven at a speed proportionate or at least bearing a fixed relation to that of the driving power, the effects just mentioned will be largely independent of the 30 speed regulation by throttle, and will take place almost solely in accordance with the torque or turning force developed.

The action of my invention is as follows: Assuming that steam from the boiler or generator is delivered through a definite opening of the throttle-valve, it will be evident that if the engine is running at a high speed, the average steam pressure exerted upon the pistons will be less than if it is running at a low 40 speed. In other words, the torque or turning force will, with a given pressure and adjustment of the throttle-valve, be greater if the speed falls slightly, such as would be the case on reaching a grade in the path traveled 45 over, or in reaching a section of the road which is heavy, *i. e.*, sandy, rutty or muddy. This increased torque of the engine strains the spiral spring 35 to a greater or less degree, and produces a relative rotation between the 50 sprocket-wheel 8 and the splined sleeve 31. The latter, as it moves laterally away from the path of the sprocket-chain, acts on the fuel and water systems in a manner to vary the deliveries, either by changing the 55 admission at the valves or by changing the effective strokes of the pumps. Conversely, if the strain on the spring 35 is relieved, as when the vehicle reaches a smooth level road, the 60 spring will uncoil or return to its normal position and the parts more nearly assume the

position illustrated in Figs. 1 and 4, and the supply of water and fuel is decreased accordingly. If the vehicle is traveling down a grade so that the sprocket-wheel and sleeve 32 are permitted to assume the position shown in Figs. 1 and 4, the supply of water and fuel will be cut down to a minimum; or if the parts be so designed the delivery of fuel and water through the valves 17 and 18 may be cut off entirely. The 70 sprockets, chain and differential gears act to transmit motion from the engine to the wheels in the ordinary manner.

In Figs. 7, 8 and 9, I have illustrated a chain-drive between the engine 1 and the rear sprocket 8, which chain is employed to effect the regulation. Bearing upon opposite sides of the chain 6 are rollers 55 which are mounted in a frame 56, that is in turn supported between the extension-springs 57, 85 the latter being attached at their outer ends to suitable supports. The frame 56 is slotted, as at 58, and working in this slot is a pin 59 that is connected to a bar 60, a guide 61 being employed to maintain the proper relation of the parts. The motion of the frame 56 up or down will so actuate the bar 60 as to cause it to move back and forth. If the direction of the drive is such that the chain 6 is tightened on the upper side, as in Fig. 8, 95 the lower spring 57 will be stretched to the utmost, the upper spring released, and the frame 56 shifted so as to cause the rod 60 to move to the extreme right. If, on the other hand, the direction of the drive is such that the lower part of the chain is tight, as in Fig. 9, this condition is reversed, and the upper spring 57 becomes stretched while the lower spring is released, and the rod 60 is moved to the right, as in the previous figures. 105 In either case, when the torque exerted by the driving element is at the maximum the rod 60 will be moved to its extreme right-hand position, and any intermediate application of power will cause the rod to assume an intermediate position. It is to be understood that the rod 60 acts upon some suitable controlling mechanism, such as the valves 17 and 18, or the sliding block 50 of Fig. 6.

In accordance with the provisions of the 115 patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is,—

1. In combination, an energy-producing 125 device, a prime mover receiving energy therefrom, a shaft, a driving connection between the prime mover and the shaft which includes a lost-motion device, and a means for regulating the production of energy by 130

the device which changes its position in accordance with changes in position of the lost-motion device.

2. In combination, a vapor generator, a fire chamber, an engine, and a means controlling the production of vapor by the generator which means is regulated in its action by the torque developed by the engine.

3. In combination, a vapor generator, a fire chamber, an engine, a means controlling the admission of liquid to the generator, a means controlling the admission of fuel to the fire chamber, and mechanism which is dependent in its action upon the torque developed by the engine for actuating both of said means.

4. In combination, a source of energy, a motor, a driven element, a driving connection between the motor and the element, a spring, which is included in the connection, and a device which is under the control of the spring and is responsive to variations in the torque of the motor for regulating the source of energy.

5. In combination, a steam generator, an engine, a driven wheel, a driving connection between the engine and the wheel, a spring which forms a part of the driving connection, and means under the control of the spring for varying the energy produced by the generator.

6. In combination, an engine, a steam generator, a driving gear, a driven wheel, a spring connection between the gear and the wheel whereby a limited independent movement is provided for between them and means acted upon by the spring connection for varying the amount of energy produced by the generator.

7. In combination, a source of energy, a motor, a driving gear and a driven wheel having a certain limited amount of independent movement, and a means actuated by the gear during the interval that the independent movement is taking place for automatically increasing the amount of energy produced by the source thereof.

8. In combination, a source of energy, a motor, a torque regulating device, a driving gear, a cam connected to the gear, a sleeve acted upon by the cam, and a lever operated by the sleeve for varying the amount of energy produced by said source in accordance with changes in torque of the motor.

9. In combination, a generator, an engine, a driven wheel, a gear mounted concentrically with the shaft of the driven wheel, a sleeve mounted on the same shaft and capable of moving longitudinally thereon under the action of the gear, a pivoted lever which is operatively connected to the sleeve, and a fuel-regulating means which is operated by the lever.

10. In combination, a boiler, a burner, an engine, water and fuel supplies, means for

regulating the admission of water to the boiler and fuel to the burner, and a device acted upon by changes in torque of the engine for varying the position of said means for regulating the amount of water and fuel delivered to the boiler and burner.

11. In combination, a boiler, a burner, an engine, sources of water and fuel supply, a throttle-valve, valves for regulating the admission of fuel to the burner and water to the boiler, a driven element, a connection between the engine and the element containing a certain amount of lost motion, and means under the control of the connection for varying the action of said valves.

12. In combination, a boiler, a burner, an engine, sources of water and fuel supply, water and fuel pumps, a driven wheel, a spring connection between the engine and the wheel whereby a certain amount of lost motion is provided, and a means under the control of the spring connection for varying the effective deliveries of the pumps.

13. In combination, a source of energy, a motor, a driven shaft, gears mounted thereon, a casing surrounding the gears and provided with a pinion meshing therewith, a hub formed on the casing, a gear-wheel sleeved on the hub, a spring connection between the gear-wheel and the hub, a sleeve which is splined on the hub of the casing, and a lever actuated by the sleeve for automatically increasing the energy produced by the source thereof when the torque of the motor increases.

14. In combination, a source of energy, a motor, a shaft driven thereby, a gear support mounted on the shaft, a gear sleeved on the hub of the support, a sleeve splined on the hub of the support, cam faces on the gear and sleeve arranged to impart lateral movement to the sleeve, a lever, and means actuated thereby to regulate the supply of energy produced by the source thereof.

15. In combination, a source of energy, a motor, a divided shaft driven thereby a system of differential gearing between the parts of the shaft, a support which carries a part of the system, a gear which is loosely mounted on the hub of the support, a spring connection between the gear and support, a piece which is moved by the gear when the spring is placed under more than a predetermined stress, a bell-crank lever attached at one end to the piece and movable therewith, and a means which is actuated by the other end of the lever for regulating the supply of energy produced by the source thereof.

16. In combination, a boiler, a burner, an engine, a fuel pump, a shaft which is driven from the engine, a lost-motion connection between the engine and shaft, a variable-stroke driving mechanism between the shaft and the pump, a lever actuated by the said

lost-motion connection, and a means actuated by the lever for varying the stroke of the pump.

17. In combination, an engine, a shaft driven thereby, a pump, a driving connection between the shaft and the pump piston, and means actuated by the engine for varying the effective stroke of the pump.

18. In combination, a boiler, a burner, fuel and water pumps for supplying water to the boiler and fuel to the burner, an engine, and a regulator controlled by the engine for controlling the effective deliveries of the pumps.

19. In combination, an energy-producing device, a prime mover receiving energy therefrom, a driven means connected to the prime mover, and a device acted upon by the said driven means for regulating the energy produced by said device.

20. A system of the character described comprising an energy-producing device, a prime mover receiving energy from the energy-producing device, the energy-pro-

ducing device and the prime mover being relatively fixed in combination with means for regulating the energy produced by the device, and a regulator which is dependent in its action upon the torque developed by the prime mover for controlling the said means.

21. In combination, a vapor generator, a fire chamber, an engine fixed in position and receiving vapor from the generator, a load driven by the engine, a power transmitting means connected to the engine, a device interposed between the means and the load which yields in response to changes in torque developed by the engine, and a means controlled by said device for regulating the vapor produced by the generator.

In witness whereof, I have hereunto set my hand, this 12th day of October, 1901.

ELIHU THOMSON.
